HIS ATTORNEYS.

UNITED STATES PATENT OFFICE.

HENRY J. VOOWIE, OF CHICAGO, ILLINOIS.

DESIGN FOR A REFRIGERATOR DISPLAY-CASE.

SPECIFICATION forming part of Design No. 25,784, dated July 14, 1896.

Application filed May 25, 1896. Serial No. 593,060. Term of patent 31 years.

To all whom it may concern:

Be it known that I, HENRY J. VOOWIE, a citizen of the United States, residing at Chicago, in the county of Cook and State of Illinois, have invented and produced a new and original Design for a Combined Refrigerator and Display-Case, of which the following is a specification, reference being had to the accompanying drawing, showing in perspective a combined refrigerator and display-case embodying my design.

In said drawing, A A represent the upright corner or frame-pieces; B, the base; C C, the feet; D, the top, and E E the horizontal members connecting the uprights A.

F is the door closing the ice-chamber, and is made with square panels, as shown at f f.

G and H are glass doors for the lower compartments of the case.

All the doors are of the same width, but the lower one is higher than the others and is substantially square in outline.

At the sides the ice-chamber is paneled in rectangular panels, as shown at f' f', and the lower compartments are made with transparent and substantially rectangular windows 25 G' and H'.

The base is ornamented with a horizontal line of molding b, through the center of which runs a plain longitudinal surface b'. The top is also provided with a line of molding d, features of which are a half-round bead d', a longitudinal recess d², and an ogee d³. The feet are cut upon an ogee curve at each side. 35

I claim—

The design for a combined refrigerator and display-case herein shown and described.

HENRY J. VOOWIE.
